CLOTHES IRONING MACHINE

Evan Hartley Stevenson, Fergus, Ontario, Canada

Application June 16, 1951, Serial No. 231,928

3 Claims. (Cl. 38—60)

1

This invention relates to an ironing machine and in particular to a table model ironing machine which is compact, light in weight, and rugged in construction.

One of the objects of the invention is to provide a table model electric ironing machine which is of such light weight that it can be easily moved from one location to another, can be used on the top of a table and is compact so that it can be stored in a small space. To this end the ironing machine which is the subject matter of the present application is constructed so that the number of operating parts and controls are reduced to a minimum and simplified in construction resulting in a portable ironing machine which is very light in weight and yet is extremely efficient in operation.

In carrying out the object of this invention, the electric ironing machine consists of a hollow base having mounted on the end thereof or formed in conjunction therewith a bracket supporting base. Mounted on the top of the base is a bracket for supporting the motor for driving the roll. The motor provided with a driving connection which rotatably supports the ironing roller, mounted within the hollow base is a shaft having a shoe supporting arm at one end which resiliently supports an electrically heated ironing shoe and an operating lever at the other end which serves a dual purpose, first to move the electrically heated shoe into and out of contact with the ironing roller and second when the shoe is moved into contact with the ironing roll to actuate the switch to energize the electric motor as soon as the shoe contacts the roller.

Other and further advantages and objects of the present invention will be ascertained from the accompanying description and the drawings which illustrate a preferred exemplification of a table model ironing machine constructed in accordance therewith. In the drawings:

Figure 1 is a perspective view of the electric ironing machine constructed in accordance with the present invention with portions of the outer surfaces cut away to illustrate and disclose certain of the operating parts in their proper assembled relationship.

Figure 2 is a sectional end view to show internal mechanism with the ironing shoe in its inoperative position.

Figure 3 is a cross sectional view on the line 3—3 Fig. 11.

Figure 4 is a plan view of the operating lever assembly.

Figure 5 is a side elevation of the operating lever assembly.

2

Figure 6 is a fragmentary front view of the base to show the operating lever at the bottom of the slot prior to being rotated into the locked position shown in Figure 7.

Figure 7 is a view similar to Fig. 6 showing the lever in the locked position with the lever cut off on the line 7—7 of Fig. 5.

The electric ironing machine illustrated in the drawing comprises a hollow base 10, a rotatable ironing roll 11, an electrically heated ironing shoe 12, a shaft 13, which carries a shoe supporting arm 14 at one end and an operating lever 15 at the other end.

The top surface of the base is sloped upwards from front to rear as indicated at 16 to form an enlarged space at the rear extending from end to end for housing the shaft 13, the arm 14, a bracket 17 for supporting the end of the shaft 13 adjacent the arm 14, and a spring 18 one end 20 of which is connected to the bracket 17 and the other end connected to the lower end of the arm 14, the spring being tensioned to normally urge the shoe out of engagement with the roller 11. The slope of the top surface of the base 10 also serves to direct the ironed clothes towards the front thereof so that the operator can readily remove the ironed clothes.

The mounting for the ironing roll 11 comprises a cylindrical bracket 19 having a base member 19a which is mounted on the bracket supporting base 20 which is formed as part of the right hand end of the hollow base 10. The bracket supporting base 20 is hollow as shown and houses the lever 15, a bracket 21 which supports the end of the shaft 13 adjacent the lever 15 and an electric switch 22 which is mounted on a bracket 22a within the supporting base 20, adjacent the lever 15. The switch 22 is provided with an operating push button 23. The switch 22 is positioned so that the push button 23 will be actuated by the lever 15 to close the circuit to the electric motor which drives the roller when the lever is actuated to move the shoe into contact with the roll. The front wall 24 of the bracket supporting base 20 is formed with a vertically extending slot 25 through which the shaft 26 of the handle 26a is entered for connection to the lever 15 in the manner hereinafter described. The free end of the lever 15 is formed with a socket 27 into which is removably entered the free end 28 of the shaft 26. In order to removably retain the end 28 in the socket 27, the end 28 is formed with a peripheral groove 29 which receives a spring 29a carried by the socket 27.

The portion of the shaft 26 which extends from the free end through the slot 25 to a short

distance beyond the wall 24 of the lever 15 and is formed with a flat section 30 which is designed to ride freely in the slot 25. The handle on each side of the flat section is larger than the slot to prevent the handle being disconnected except when the lever has been moved to the position which in the present construction is at the top end of the slot 25 and when the shoe is out of engagement with the ironing roll. To allow the handle to be removed, the top end of the slot is enlarged as indicated at 25a. The top and bottom edges 31, 32 respectively of the flat section 30 are cut on a radius. As will be seen from the following description, the slot 25 is formed to effect a turning action of the shaft 26 which causes the surface 31 to actuate the push button 23 closing the circuit to the motor as herein-after described. To effect the turning action of the shaft 26 and the actuation of the switch in an automatic manner, the following related parts are employed. In the first place, that part of the shaft which extends outwardly from the flat section 30 is inclined with respect to the longitudinal axis of the lever 15 and the flat section 30 as shown in Figure 3. It has been found that a three degree incline is sufficient. As illustrated in Figures 6 and 7 the lower end of the slot 25 is enlarged as shown to allow the operating handle to rotate about its longitudinal axis. This enlarged lower end forming a terminal recess identified by the numeral 33a. This enlarged portion is shaped to have the same general configuration in cross section as the flat section 30 in transverse cross section and arranged at 45° clockwise from the perpendicular so as to allow approximately a 45 degree rotation clockwise of the shaft 26 and flat section 30 at which point further rotation is stopped by the face 34a. As the handle is offset, the rotation thereof as it is pressed downward is effected automatically as the flat section 30 enters the terminal recess 33a. The rotation of the shaft has an eccentric action to bring the surface 31 into engagement with the push button 23 actuating it to close the circuit to the electric motor. The offset handle also serves to lock the shoe in contact with the ironing roller during the ironing operation. However it is designed as illustrated so that by a slight upward pressure on the handle the following action takes place automatically and in consequence: The flat section is released from the terminal recess 33a of the slot rotating the handle anti-clockwise moving the surface 31 out of engagement with the push button 23 thus opening the circuit to the electric motor and allowing the handle to move to the top end of the slot permitting the shoe to be moved out of engagement with the roller by the combined action of the upward pressure and the spring 18.

The bracket 19 carries an electric motor (not shown) so designed that the hollow rotatable roll will surround the motor the roll being provided with an internal bracket which is connected to and supported by the motor. As this type of mounting and connection is standard practice in the construction of table model electric ironers the specific construction and details of mounting have not been shown as they do not form any part of the present invention.

The electrically heated shoe 12 is curved to correspond to the curvature of the roll 11 and is secured to a plate 33 which encloses an electric heating element for heating the shoe. The plate is connected to the free or upper end of the shoe supporting arm 14 by the following parts. The arm 14 is made in the form of a channel and its

upper or free end is arcuately curved inwardly and is provided with a supporting member 34 pivotally connected between the sides of the arm 14 adjacent the free end thereof by the pivot pin 35. The supporting member 34 has attached thereto below the pin 35 an elliptical spring 36. The free ends of the spring 36 resiliently support the ironing shoe by the following apparatus. Removably connected to the plate 33 is a pair of inverted U-shaped members 38, 38a which are positioned so that the ends of the spring will be received in a slide-way 39 formed by bending each arm of each U-shaped member adjacent the plate 33 as shown clearly in Figure 1. Carried on the plate 33 is a pair of stop members 40, one adjacent each end of spring and positioned to allow a predetermined flexing of the spring and then act as a stop member to allow the full spring pressure to be exerted on the shoe during the ironing operation. In the present instance, the stop members consist of bolts 43 projecting through the plate 33. The spring tension may be adjusted by the adjusting screw 44. The spring 36, members 38, 38a and the upper end of the arm 14 are enclosed by a cover 42 which may be secured in place by means of machine screws 45 entered through the top of the cover and threaded into the top end of the members 38, 38a.

In Figure 1, the ironing machine is shown in the position for effecting an ironing operation. In that position, it will be seen, that the ironing shoe 12 is against the roller and the handle 26a has been depressed causing the surface 31 to actuate the switch 22, closing the electric circuit to the electric motor which is mounted so as to lie within and support the roller 11. When the ironing shoe and ironing roll are out of engagement the handle is at the top end of the slot 25. The push button 23 has its outer end lying in close proximity to the terminal recess 33a of the slot 25 but positioned so that the flat section 30 of the handle will not touch the push button as the handle is depressed. When the operator wishes to effect an ironing operation, he or she depresses the handle 26a and as the flat section enters the terminal recess 33a of the lower end of the slot 25, the handle automatically rotates clockwise on its longitudinal axis bringing the top face 31 into engagement with the push button 23 to close the electric switch 22 and thus energize the motor for driving the ironing roll. It will also be seen that the handle is locked in this position since by reason of its construction, as hereinbefore mentioned, it has a natural tendency to continue its clockwise rotation. To release the shoe from its ironing position and simultaneously stop the electric motor, all that is necessary is a slight upward pressure on the handle 26 which will release it from the ironing position and cause it to move to the upper end of the slot 25.

What I claim as new and desire to protect by Letters Patent of the United States is:

1. For an electric ironing machine having a base, a housing mounted on said base and formed with a bracket extending horizontally above said base, a rotatable ironing roll supported by said bracket for rotation about a horizontal axis, an electric motor for rotating said roll, and an electrically heated ironing shoe mounted on a rotatable shaft for movement into and out of operative engagement with the ironing roll; means for moving said shoe into and out of engagement with said roll and for simultaneously therewith either starting or stopping said motor comprising

a guide slot formed vertically in the front wall of said housing and having at the lower end an arcuate terminal recess, a manually operated articulated control lever connected to said shaft and extending outwardly through said slot for moving said shoe into and out of engagement with said roll, said lever having a flat section guided in said slot when said shoe moves into and out of operative engagement and rotating said lever when the flat section enters the terminal recess and locks said lever in operative engagement with said roll, an electric switch for said motor positioned in the housing adjacent said terminal recess, a switch actuating surface on said lever positioned to actuate said switch when said lever moves the shoe into and out of operative engagement with the roll to energize and de-energize said motor respectively.

2. For an electric ironing machine according to claim 1 in which the part of the lever which projects outside the slot is inclined from the longitudinal axis of the lever in a direction that downward manual pressure on the lever will rotate the lever in said terminal recess.

3. For an electric ironing machine having a base, a housing mounted on said base and formed with a bracket extending above said base, a rotatable ironing roll supported by said bracket for rotation about a horizontal axis, an electric motor for rotating said roll, an electric switch for energizing said motor and an electrically heated ironing shoe mounted on a rotatable shaft for

movement into and out of engagement with the ironing roll; means for actuating said shoe and simultaneously operating said switch comprising a manually operated control lever connected to and extending at right angles from said shaft for rotating said shaft to move said shoe into and out of engagement with said roll, said lever being articulated for rotative movement about its longitudinal axis, a guide slot formed in the front wall of said housing through which said lever projects and in which said lever rides during its manipulation to move said shoe into and out of its operative position, said slot having a terminal recess at the terminal of the operative movement of said lever, said switch being located in the housing adjacent the terminal recess, a switch actuating surface on said lever positioned to actuate said switch when said lever rotates in said terminal recess as the shoe moves into and out of operative engagement with the roll thereby energizing and de-energizing said motor.

EVAN HARTLEY STEVENSON.
